CLAIM

The ornamental design for a dog training device set, as shown and described.

DESCRIPTION

FIG. 1 is a perspective view of a dog training device set consisting of a remote controller and a receiver according to the present application;

FIG. 2 is an upper perspective view of a dog training device set, with the remote controller shown in isolation for clarity of disclosure;

FIG. 3 is a lower perspective view of the remote controller of FIG. 2;

FIG. 4 is a front elevational view of the remote controller of FIG. 2;

FIG. 5 is a rear elevational view of the remote controller of FIG. 2;

FIG. 6 is a left side elevational view of the remote controller of FIG. 2;

FIG. 7 is a right side elevational view of the remote controller of FIG. 2;

FIG. 8 is a top plan view of the remote controller of FIG. 2;

FIG. 9 is a bottom plan view of the remote controller of FIG. 2;

FIG. 10 is an enlarged view of portion 10 shown in FIG. 3;

FIG. 11 is an upper perspective view of a dog training device set, with the receive shown in isolation for clarity of disclosure;

FIG. 12 is a lower perspective view of the receiver of FIG. 11;

FIG. 13 is a front elevational view of the receiver of FIG. 11;

FIG. 14 is a rear elevational view of the receiver of FIG. 11;

FIG. 15 is a left side elevational view of the receiver of FIG. 11;

FIG. 16 is a right side elevational view of the receiver of FIG. 11;

FIG. 17 is a top plan view of the receiver of FIG. 11; and,

FIG. 18 is a bottom plan view of the receiver of FIG. 11.

The dash-dash broken lines in the drawings depict portions of the dog training device set that form no part of the claimed
